CLAIM

The ornamental design for a kitchen device, as shown and described.

DESCRIPTION

FIG. 1 is a perspective view of a kitchen device, shown in closed condition;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an exploded perspective view thereof, shown in open condition;

FIG. 9 is an exploded front view thereof, shown in open condition;

FIG. 10 is an exploded rear view thereof, shown in open condition;

FIG. 11 is an exploded left-side view thereof, shown in open condition;

FIG. 12 is an exploded right-side view thereof, shown in open condition;

FIG. 13 is an exploded top view thereof, shown in open condition; and,

FIG. 14 is an exploded bottom view thereof, shown in open condition.

The broken lines in the figures illustrate the portions of the design that form no part of the claimed design.
